JOHN H. ROELKER, OF EVANSVILLE, INDIANA.

Letters Patent No. 88,213, dated March 23, 1869.

IMPROVEMENT IN GRATES FOR COOKING-STOVES.

The Schedule referred to in these Letters Patent and making part of the same.

To all whom it may concern:

Be it known that I, JOHN H. ROELKER, of Evansville, in the county of Vanderburgh, and State of Indiana, have invented a new and useful Improvement in Stoves; and I do hereby declare that the following is a full, clear, and exact description of the construction and operation of the same, reference being had to the accompanying drawings, making a part of this specification, in which—

Figure 1 is a vertical section through the line xx of fig. 2.

Figure 2 is a plan.

The object of this invention is to improve the construction of cooking-stoves in such a manner, that when the "fire-bottom" burns out, and has to be thrown away, the whole of it need not be thus rendered useless, but the burnt portion can be removed, and another piece, of similar construction, substituted in its place, while the hearth, and other portions not destroyed, remain undisturbed.

This object is readily accomplished, by casting the fire-bottom and hearth in two or more pieces, instead of one, as heretofore. When one of the pieces becomes worthless, it can be removed, and another casting from the same mould put in its place. When properly constructed, the fire-bottom and hearth thus made are as unobjectionable in every respect as the old one, and in some particulars possess important advantages over it.

In the drawings, which represent a fire-bottom and hearth constructed in two pieces, riveted together by means of overlapping flanges adapted to the purpose,

A designates the front piece, which is least exposed to the fire, and

B, the inner piece, nearly all of which is immediately in contact with the fire, and liable to be destroyed long before the outer part, A, is injured.

These parts are connected together by one or more screws or rivets, c c, passing through flanges a a, b b.

The part B is cast with ridges, e e, on which the fuel rests, and the parts A and B, when they come together, form a chamber at i, which constitutes the ashpan. The form of the combined apparatus is therefore in no respect different from that heretofore employed, and may be modified, as desired, to adapt it to different kinds of stoves.

Four important advantages result from my improved construction: First, the burnt part, B, can be taken out without sacrificing the part A; secondly, either part, if accidentally cracked and spoiled, can be removed, without throwing away the other part; thirdly, the castings, being smaller, will not so readily crack from unequal heating; and fourthly, the joint gives an opportunity for the heated part to expand, and at the same time, in some degree, prevents the conduction of the heat to the other part, thereby preventing the fracture of the castings by unequal expansion.

From these facts, the stove is evidently much more economical than those heretofore manufactured, and not so liable to get out of order, and give its owner inconvenience and trouble.

Having thus described my invention,

What I claim as new, and desire to secure by Letters Patent, is—

As an article of manufacture, the "fire-bottom" herein described, consisting essentially of the parts A and B, united by the flanges a b, and screws or rivets c, and adapted to operate together, substantially as and for the purposes herein described.

To the above specification of my invention, I have signed my hand, this 22d day of January, 1869.

JOHN H. ROELKER.
